Attorney

UNITED STATES PATENT OFFICE

MATTIE JANE HEWITT, OF NEW ORLEANS, LOUISIANA

PORTABLE REFRIGERATOR

Application filed May 29, 1929. Serial No. 366,980.

The invention relates to a refrigerator cover for barrels and other receptacles, and the present application is filed to take the place of an application filed by me August 5 9, 1928, Serial Number 298,585, for the same invention.

The object of the present invention is to provide a simple, practical and efficient food receptacle cover of strong, durable and comparatively inexpensive construction, designed for use on barrels and other receptacles for the shipment of fish, poultry, meats, eggs and other perishable goods, and adapted to be readily applied to and removed from a barrel without injury to the refrigerator cover and capable of maintaining the entire contents of the barrel or other receptacle at the desired temperature, so that such articles of food may be shipped without liability of 15 spoiling them in transit.

A further object of the invention is to provide a refrigerator cover of this character adapted to be re-iced during transit without removing it from the barrel and capable of 20 draining the ice water without permitting the same to come in contact with the contents of the shipping receptacle.

Another object of the invention is to provide a refrigerator cover for barrels adapted 25 to extend from the top to the bottom of a barrel and capable of feeding ice by gravity from the top to the bottom, and equipped at the top with an ice hopper adapted to hold a relatively large amount of ice so that frequent re-icings will not be required.

It is also an object of the invention to provide a refrigerator cover for barrels and other receptacles adapted to be compactly arranged for returning the device to the 30 shipper and provided with means for holding a shipping tag and capable of maintaining the tag in an exposed position both when the refrigerator cover is in use on a barrel and when in folded condition for returning 35 the device to the shipper.

With these and other objects in view, the invention consists in the construction and novel combination and arrangement of parts hereinafter described, illustrated in the accompanying drawings, and set forth in the

claims hereto appended, it being understood that various changes in the form, proportion, and minor details of construction, within the scope of the claims, may be resorted to without departing from the spirit of the invention or sacrificing any of the advantages thereof.

In the drawings:

Figure 1 is a perspective view of a refrigerator cover for barrels constructed in accordance with this invention and showing the cover attached to the barrel.

Fig. 2 is a central vertical sectional view of the same.

Fig. 3 is a side elevation of the refrigerator cover, the lower portion of the metal tubular section being broken away and the upper part of the flexible section being in section.

Fig. 4 is a side elevation, partly in section, showing the refrigerator device in folded position.

Fig. 5 is a detail sectional view illustrating the manner of securing the refrigerator device in folded position.

In the accompanying drawings, in which is illustrated the preferred embodiment of the invention, the refrigerator cover comprises in its construction a lower tubular metallic section 1 and an upper flexible section 2 constructed of canvas or other suitable fabric and adapted to be collapsed and folded and arranged within the lower tubular section 1 for return to the shipper or other person, as illustrated in Fig. 4 of the drawings.

The lower section 1 consists of a pipe or tube of iron or other suitable material, and it may be tapered and cylindrical in cross section, as illustrated in the accompanying drawings, or of any other desired configuration, as will be readily understood, and when the device is in use it is arranged within a barrel 3 and extends from the bottom of the barrel to the upper portion thereof, as clearly illustrated in Fig. 2 of the drawings. The lower end of the tubular section 1 is secured to the bottom 4 of the barrel by being arranged in an opening 5 thereof. The tubular section is provided at its lower end with a bottom wall 6 having perforations 7 forming drain openings and adapted to permit the ice water to

drain from the device without emptying the barrel or coming in contact with the contents thereof. The side walls of the tubular lower section are imperforate between the bottom of 5 the barrel and the upper flexible section so that the ice water cannot leak or pass into the barrel.

The flexible upper section 2 has a tapered lower portion 8 extending downwardly from 10 the top of the barrel and terminating in a substantially cylindrical neck 9 which is secured within the upper end of the tubular section 1 by suitable lacing 10 which passes through spaced perforations 11 of the tubular section 15. The extension neck 9 covers the perforations 11 and closes the same at the inner face of the tubular section 1 and prevents any leakage of water through the said perforations. The flexible section 2 may, however, be secured 20 to the lower tubular section in any other desired manner, as will be readily understood. The upper portion of the flexible receptacle extends normally above the top of the barrel, as clearly illustrated in Figs. 1 and 2 of the 25 drawings, and is substantially cylindrical, the side walls being preferably arranged at a slight inclination and defining a slight taper, but the normally projecting upper portion of the flexible section of the device may be of any 30 other desired configuration, and it is provided with a horizontal top wall 12 composed of two substantially semi-circular sections having diametrically arranged contiguous edges 13 provided with suitable eyelets 14 receiving a 35 suitable lacing 15 which is adapted to enable the refrigerator cover to be readily opened and re-iced in transit without removing the refrigerator cover from the barrel 3.

The enlarged flexible upper section of the 40 device forms an ice hopper and is adapted to hold a considerable quantity of ice for enabling the contents of the barrel to be maintained in the desired temperature without frequent re-fillings of the device. The diameter of the enlarged upper section of the 45 refrigerator cover is designed to be slightly less than that of the top of the barrel, and it is provided with a flaring apron 16 of canvas preferably formed integral with the 50 adjacent portion of the upper flexible section and connected with the same by a substantially horizontal portion 17 which extends from the juncture of the tapering portion 8 and the upper projecting portion of 55 the flexible hopper section of the device. The flaring apron conforms generally to the taper of the upper portion of the barrel, as clearly shown in Fig. 2 of the drawings, and it is secured thereon by a barrel hoop 18 60 which tightly clamps the apron on the barrel at the upper edge thereof. The flexible upper section of the device is provided at intervals with tabs or ears 19 having eyelets 20 through which are driven nails 21 or other 65 suitable fastening devices which terminate

short of and do not pierce the apron 16, as clearly illustrated in Fig. 5 of the drawings.

The refrigerator cover is provided at the top with a projecting ear 22 having a suitable eye 23 and adapted to receive a shipping tag 24 and capable of exposing the shipping tag when the refrigerator cover is in use and also when the flexible upper section of the refrigerator cover is folded and arranged within the tubular metal section 70 75 1, as illustrated in Fig. 4 of the drawings.

What I claim is:

1. A refrigerator cover for portable receptacles comprising a lower tubular section designed to be mounted in an opening in the bottom of a receptacle and to extend to the upper portion thereof and provided with drain openings arranged exteriorly of the receptacle, an enlarged upper flexible hopper section foldable within the lower tubular section and normally extending above the receptacle, said hopper section being adapted to hold a supply of ice and secured to and communicating with the lower tubular section, the side walls of the latter being imperforate from the hopper section to the bottom of the said receptacle, and means for securing the hopper section to the top of the receptacle and for closing the same exteriorly of the hopper section. 90 95

2. A refrigerator cover for portable receptacles comprising a rigid tubular lower section and a flexible upper hopper section having a tapered lower portion arranged within the lower portion of the receptacle and secured to the upper end of the lower tubular section, said hopper section normally projecting exteriorly of the receptacle and adapted to contain a refrigerant and to feed the same downward by gravity, and an apron connected with the flexible hopper section and extending outwardly therefrom and cooperating therewith to form a cover for the receptacle. 100 105

3. A refrigerator cover for portable receptacles comprising a rigid tubular lower section and a flexible upper hopper section having a tapered lower portion arranged within the lower portion of the receptacle and secured to the upper end of the lower tubular section, said hopper section normally projecting exteriorly of the receptacle and adapted to contain a refrigerant and to feed the same downward by gravity, and an apron surrounding the hopper section and extending outwardly therefrom and cooperating therewith to form a cover for the receptacle and provided with a flaring portion adapted to be arranged exteriorly of the receptacle and to be clamped thereon by a hoop thereof. 110 115 120

4. A refrigerator cover for portable receptacles comprising a rigid tubular lower section and a flexible upper hopper section having a tapered lower portion arranged within the lower portion of the receptacle 125 130

- and secured to the upper end of the lower tubular section, said hopper section normally projecting exteriorly of the receptacle and adapted to contain a refrigerant and to feed 5 the same downward by gravity, an apron surrounding the hopper section and extending outwardly therefrom and cooperating therewith to form a cover for the receptacle and provided with a flaring portion adapted to be 10 arranged exteriorly of the receptacle and to be clamped thereon by a hoop thereof, and flexible ears projecting from the hopper section and arranged to extend over the said hoop and adapted to receive fastening devices for securing them to the hoop. 15
5. A refrigerator cover for portable receptacles comprising a rigid lower tubular section and an upper enlarged hopper section constructed of flexible material and secured 20 to the lower tubular sections, said hopper section being provided with a flexible top wall having fastening means and adapted to be opened to permit the device to be re-iced without removing it from the receptacle. 25
6. A refrigerator cover for portable receptacles comprising a rigid lower tubular section and an upper flexible section having tapered lower portion terminating in a neck secured to the upper end of the lower tubular section, said hopper section normally projecting beyond the receptacle and provided with an exteriorly arranged flexible apron cooperating with the hopper section to cover the top of the receptacle, said hopper section 35 and apron being foldable within the lower tubular section when not in use. 30
7. A refrigerator cover for portable receptacles comprising a rigid lower tubular section and an upper flexible section having 40 tapered lower portion terminating in a neck secured to the upper end of the lower tubular section, said hopper section normally projecting beyond the receptacle and provided with an exteriorly arranged flexible apron 45 cooperating with the hopper section to cover the top of the receptacle, said hopper section and apron being foldable within the lower tubular section when not in use, and a tag receiving ear projecting from the top of the 50 hopper section and arranged to expose a shipping tag when the hopper section is arranged for use and also when folded into the lower tubular section. 55
8. A portable refrigerator comprising a receptacle and a cover therefor, the cover comprising a lower tubular section located within the receptacle and an upper hopper section constructed of flexible material, said hopper section being adapted to project above the 60 top of the receptacle and having an exteriorly arranged flexible apron cooperating with the upper hopper section to cover the top of the receptacle, said hopper section and apron being foldable within the lower tubular section 65 when not in use. 65
9. A portable refrigerator comprising a receptacle and a cover therefor, the cover comprising a lower tubular section located within the receptacle and an upper hopper section constructed of flexible material, said hopper section being adapted to project above the top of the receptacle and having an exteriorly arranged flexible apron cooperating with the upper hopper section to cover the top of the receptacle, said hopper section being provided with an opening and having fastening means to maintain said opening closed, said hopper section and apron being foldable within the lower tubular section when not in use. 70
10. A portable refrigerator comprising a receptacle, a tubular member within the receptacle, a flexible member adapted to project above the top of the receptacle and having a closable opening therein and having communication with said tubular member and also having connection with the walls of the receptacle whereby to completely close the receptacle and when not in use adapted to be folded and placed within said tubular member. 80
11. A portable refrigerator comprising a receptacle, a tubular member within the receptacle, a flexible member adapted to project above the top of the receptacle and be maintained projected above the receptacle by a commodity within the refrigerator, said flexible member having connection with said tubular member and also having connection with the walls of said receptacle to completely close the latter. 85
12. A portable refrigerator comprising a receptacle, a tubular member within the receptacle, a flexible member having connection with the upper end of the tubular member and also having connection with the side walls of the receptacle to close the same, the flexible member having an opening, and means to maintain the opening closed. 90
- In testimony whereof I have hereunto set my hand this 27th day of May, 1929. 105
